UNITED STATES PATENT OFFICE.

HEINRICH WEISS, OF VIENNA, AUSTRIA-HUNGARY.

OIL-TRANSFORMER.

1,104,723.

Specification of Letters Patent. Patented July 21, 1914.

Application filed October 28, 1913. Serial No. 797,703.

To all whom it may concern:

Be it known that I, HEINRICH WEISS, electrical engineer, and a subject of the Emperor of Austria-Hungary, residing at Karl 5 Ludwigstrasse No. 4, Vienna, XVIII, Austria-Hungary, have invented certain new and useful Improvements in Oil-Transformers, of which the following is a specification.

Experience has shown that in oil transformers, and in other electrical apparatus working with oil, the air above the oil has a bad influence upon the quality of the latter and as a consequence a number of experiments to chemically purify the air 10 (above the oil) have been made. It is clear that there can be no bad influence on the part of the air upon the oil, if the oil receptacle does not contain any air. Experience has shown further, that there is a danger 15 of the cooling medium affecting the oil, and spoiling it, if refrigerating coils are used.

Bearing these two facts in mind, the object of the present invention is to provide 20 arrangements by means of which not only contact of the air with the oil is prevented, but there is no air at all contained in the receptacle. In addition to these arrangements provision is made for the expansion 25 of the oil on its becoming warm; and by creating a higher pressure in the oil than in the cooling medium, a mixing of the two is prevented.

In the drawings are shown, diagrammatically by way of example several methods 30 of carrying out the object of the invention.

Figures 1 and 2 show the transformers provided with a weight. Fig. 3 shows a transformer receptacle with a cooling body 40 accessible from the exterior.

In accordance with the invention, the transformer receptacle 1 is entirely filled with oil so that no air remains in its interior. For the simplest method of execution a receptacle entirely closed and of an appropriate thickness provided with an opening for filling and an outlet for the expansion of the air, both of which are closed as soon as the oil reaches the cut off 45 valve in the filling tube, would be sufficient. If provision for the tendency to expand of the oil on becoming warm has to be made, a piston is provided at the side of the receptacle, which always displaces itself according to the volume of the oil. In the 50 method shown in Fig. 1 a cylinder 2 with

a piston 3 carrying a weight 10 is provided, which piston moves up or down according to whether the volume of the oil increases or decreases. In place of the weight, gas-pressure, liquid-pressure or spring-pressure can be applied. Further, a number of transformers can have a common cylinder 2 which is in connection with all of them by suitable connections.

In order to fill the receptacle the piston can be temporarily maintained in a higher position than it would occupy when the transformer receptacle is filled, in accordance with my invention and on the oil almost reaching the filling opening, the piston 3 is released and by its pressure raises the level of the oil over the cut-off valve of the filling opening 7, which is then closed. When the oil flows through the 75 pipe 8 into the collecting receptacle 9 the cut-off valve of the pipe 8 is also closed and no air remains in the oil receptacle. The pressure of the movable piston is at the same time utilized to create a higher pressure 80 in the oil than in the cooling medium, which is conveyed through the transformer receptacle by cooling coils 5. The higher pressure of the oil guarantees that the cooling medium will not penetrate through the 85 cooling body and mix with the oil. The pressure of the oil can be read on a pressure gage 6, and if water is used as the cooling medium, by suitably causing it to gravitate slightly it can be easily ascertained whether the water which flows out 90 visibly contains oil.

In order to prevent the necessity of having to use heavy weights, a lever connection can be applied: In Fig. 2 is shown for this 95 purpose a segment 12 gearing into the end of the piston rod, pivoting on the fulcrum 13 and having an arm 14, which carries a chain or rope with a weight 16 guided over the curved part 15. The radius of this curve 100 is in proportion to the distance from the pivot 13, so that the pressure remains the same for any position of the piston. Lever 14 can, however, also press directly on the piston rod.

Instead of arranging the cooling body in the interior of the transformer arrangements could be made whereby the wall 16 projects inwardly and forms a receptacle which is accessible from the exterior. This 110 receptacle contains the cooling medium 17 (Fig. 2) which can be constantly renewed

or cooled by means of a cooling body 18 (Fig. 3). In this case oil can also be used as a cooling medium.

To insure tightness at the places where the transformer cables enter into the receptacle 1, sockets or sleeves 20 similar to the well known cable sockets and having an attaching flange 19, are used. It will be found advantageous to provide a cut-off valve 21 in the connection pipe between receptacles 1 and 2 so that repairs of the receptacle 2 can, in case of use, be carried out, without having to put the whole apparatus out of use.

Having now described my invention what I claim as new is:

1. In an oil transformer, a closed receptacle containing a transformer, an expanding chamber, a passage connecting the bottom of said receptacle with the bottom of said expanding chamber establishing communication between the two, said receptacle adapted to be completely filled with oil, thereby

excluding all air, said oil also filling said passage and said expanding chamber, a movable piston in said expanding chamber adapted to completely cut off the expanding oil from the outside air, substantially as described.

2. In an oil transformer a closed receptacle containing a transformer, an expanding chamber in communication with said receptacle, oil adapted to so completely fill said receptacle and said chamber as to exclude any air, means for cooling said oil in said receptacle and a movable piston in said expanding chamber adapted to cut off the expanding oil from the outside air and maintain oil at a higher pressure than the cooling means, substantially as described.

In testimony whereof I affix my signature in presence of two witnesses.

HEINRICH WEISS.
